(57) **CLAIM**

The ornamental design for a display screen or portion thereof with graphical user interface, as shown and described.

DESCRIPTION

The file of this patent contains at least one drawing executed in color. Copies of this patent with color drawing(s) will be provided by the Office upon request and payment of the necessary fee.

FIG. 1 is a front view of a first image in a sequence of a first embodiment of a display screen or portion thereof with a graphical user interface showing the claimed design.

FIG. 2 is a front view of a second image thereof.

FIG. 3 is a front view of a third image thereof.

FIG. 4 is a front view of a fourth image thereof.

FIG. 5 is a front view of a fifth image thereof.

FIG. 6 is a front view of a sixth image thereof.

FIG. 7 is a front view of a seventh image thereof.

FIG. 8 is a front view of an eighth image thereof.

FIG. 9 is a front view of a ninth image thereof.

FIG. 10 is a front view of a first image in a sequence of a second embodiment of a display screen or portion thereof with a graphical user interface showing the claimed design.

FIG. 11 is a front view of a second image thereof.

FIG. 12 is a front view of a third image thereof.

FIG. 13 is a front view of a fourth image thereof.

FIG. 14 is a front view of a fifth image thereof.

FIG. 15 is a front view of a sixth image thereof.

FIG. 16 is a front view of a seventh image thereof.

FIG. 17 is a front view of an eighth image thereof; and,

FIG. 18 is a front view of a ninth image thereof.

The appearance of the animated image sequentially transitions between the images shown in FIGS. 1-9 in a sequence. FIGS. 1-9 form a first embodiment of a graphical user interface (GUI) in which color is claimed. FIGS. 10-18 form a sequence of a second embodiment of the GUI. The tonal shading in FIGS. 10-18 illustrates a contrast in appearance. The subject matter in this patent includes a process or period in which an image changes into another image. This process or period forms no part of the claimed design.

The broken line showing of a display screen and broken line showing of outlines and text are included for the purpose of illustrating portions of the article and form no part of the claimed design. The faded portions within broken lines form no part of the claimed design.
